UNITED STATES PATENT OFFICE.

CHARLES D. SHAIN, OF ROCKAWAY PARK, NEW YORK.

VAPORIZER OR CARBURETER FOR GAS-ENGINES.

SPECIFICATION forming part of Letters Patent No. 792,670, dated June 20, 1905.

Application filed March 7, 1905. Serial No. 248,791.

To all whom it may concern:

Be it known that I, CHARLES D. SHAIN, a citizen of the United States, and a resident of Rockaway Park, in the county of Queens and 5 State of New York, have invented a certain new and useful Vaporizer or Carbureter for Gas-Engines, of which the following is a specification.

My invention relates to improvements in 10 vaporizers or carbureters in which a valve or sprayer is used in connection with a means of adjustment; and the objects of my improvement are, first, to provide a ball valve or sprayer which is automatically operated; second, to afford facilities for regulating the lift 15 of said ball valve or sprayer; third, to provide an automatically-operated intake for air; fourth, to provide means for controlling the amount of gasoline or liquid fuel entering the 20 vaporizer or carbureter; fifth, to provide means for throttling or controlling the amount of gas, after same is formed, entering the cylinder of the engine; sixth, to provide means for controlling the amount of gasoline supplied 25 to the vaporizer or carbureter in conjunction with the amount of gas entering the cylinder of the engine. I attain these objects by the mechanism illustrated in the accompanying drawings, in which—

30 Figure 1 is a vertical section of the vaporizer or carbureter. Fig. 2 is a section through the vertical section of Fig. 1 at X. Fig. 3 is a perspective view.

Similar letters refer to similar parts throughout the drawings.

35 In Fig. 1 the ball A in the mixing-chamber U forms part of the valve and acts as a sprayer. It is seated to one-half its diameter in the support B. The lift of the ball A is caused by 40 the suction of the engine through the gas-outlet C and the pressure of the gasoline in the tube D.

The sliding rods E and E are connected at 45 the top by a concave piece F, which fits the top of the ball A. The sliding rods E and E pass through holes in the support B and then pass through a bottom piece G and are secured to the ring H. The thumb-nut I has a thread on the inside and is screwed up and 50 down on the tube D to permit an adjustment

of the lift of the ball A caused by suction of the engine at the gas-outlet C and an adjustment of the lift of the ball A caused by the pressure of the gasoline in the tube D.

J is one of two semicircular shutters in the 55 air-chamber K, one hinged on each side of the bottom piece G and raised or lowered automatically by the suction of the engine through the gas-outlet C.

The two halves of the vaporizer or car- 60 bureter are bolted together at Z Z.

L is a cock with a lever M connected to the tube D to control the amount of gasoline flowing through it. The lever M has a hole near its end m. (See Fig. 3.)

N, Fig. 1, is a hollow half-sphere pivoted at 65 two sides O O and connected to the lever P, at one end of which is a stud R, (see Fig. 3,) to which is connected the rod S, with an eye fitting over the stud R. This rod passes 70 through the hole m in the lever M. The rod S has two stops T and T, so that the levers P and M may be moved in conjunction, their relative movements being regulated by the placement of the stops T and T.

The pressure of gasoline, if sufficient, on the ball A, Fig. 1, through the tube D will cause 75 the ball A to rotate and the gasoline will be sprayed around the surface of the ball A, materially assisting vaporization in the formation 80 of gas.

This vaporizer or carbureter can be made in several ways; but I prefer to carry out this feature of my invention as shown in Fig. 1. It can be used either with or without a 85 float V, Fig. 3, placed in the pipe-line y y between it and the gasoline-tank Y, this arrangement of the float V, shown in the drawing Fig. 3, forming no part of my invention.

What I do claim as my invention, and desire 90 to secure by Letters Patent, is—

1. In a vaporizer or carbureter, a ball located in the mixing-chamber and a supporting-seat and a tube for gasoline or liquid fuel discharging under the ball; the lift of the ball 95 being automatically caused both by suction of the engine and pressure of the gasoline in the tube under it, all substantially as set forth.

2. In a vaporizer, or carbureter, a ball located in the mixing-chamber and seated in a 100

support and a tube for gasoline or liquid fuel discharging under the ball and sliding rods to control the lift of the ball, moved by a thumb-screw situated below the bottom of the air-chamber, all substantially as set forth.

3. The combination in a vaporizer or carbureter of a ball seated in a support and a tube for gasoline or liquid fuel discharging under the ball and sliding rods to control the lift of the ball, moved by a thumb-screw below the bottom of the air-chamber, with two shutters hinged to the bottom of the vaporizer or car-

bureter to automatically control by suction from the engine, the quantity of air taken into the air-chamber, all substantially as set forth.

Witness my hand this 6th day of March, 1905, at the city of New York, in the county and State of New York.

CHAS. D. SHAIN.
